DEVICE FOR FEEDING HEATED ROOMS
WITH WATER VAPOR

Michel Cohendy, Paris, France

Application October 1, 1932, Serial No. 635,836
In France October 31, 1931

1 Claim. (Cl. 299—20)

The present invention concerns a device for feeding water vapor to the atmosphere of rooms heated through a heat generator or radiator. The device according to my invention is chiefly characterized in that it comprises an absorbing and evaporating flat element the bottom of which is immersed in a liquid bath and which is applied either vertically or obliquely against the heating surfaces of the generator or radiator so as thus to ensure the absorption and then the evaporation of the liquid. The device according to my invention has the advantage of being not too apparent, because it is possible to conceal it between the elements of which are composed most of the heat generators or radiators.

According to a preferred embodiment of my invention, the absorbing element is applied against a support which is directly in contact with the heat generator or radiator.

My invention also comprises other characteristics which will result from the following description.

A preferred embodiment of my invention will be hereinafter described with reference to the accompanying drawing, given merely by way of example, and in which:

Fig. 1 is a perspective view of the device according to my invention fitted to a heat radiator such as those generally used in central heating plants;

Figs. 2 and 3 are an elevational front view and a side view respectively of the device according to my invention;

Figs. 4 and 5 are an elevational front view and a side view respectively of the absorbing element of the device according to my invention.

The device for feeding vapor to the atmosphere of a heated room according to my invention essentially comprises an absorbing and evaporating flat element shown separately in Figs. 4 and 5, and a metallic support 2 (Figs. 2 and 3) through which said support is thermally connected with the heat radiator or generator 3 shown in dotted lines in Fig. 1.

The absorbing and evaporating element 1 consists of a substance having a porous texture, for instance asbestos, having a very high power of absorption and evaporation. The metallic support 2 for said element 1 comprises a back 4 (Figs. 2 and 3) the vertical edges of which are bent so as to form grooves 5¹, 5² (Figs. 2 and 3) which are adapted to receive and to hold in position the absorbing element against said back 4.

The lower part of the metallic support 2 forms a

receptacle 6 into which a certain quantity of liquid is poured.

The absorbing element is placed in such manner that its lower portion is immersed in the liquid present in receptacle 6 so that the liquid is absorbed in an upward direction by the porous material of the absorbing element. Said element is applied against back 4 which is in contact with the heat radiator 3, and consequently it is constantly heated and its capacity of absorbing and evaporating the liquid is considerably increased by the elevation of temperature that is imparted thereto through back element 4 which acts as a support and as a heating plate.

The absorbing power of element 1 can be maintained by adding to the liquid of receptacle 6 some drops of glycerin. Obviously any other substance improving the absorbing qualities of the matter of which is made element 1 may be utilized.

It should be well understood that the important thing is that the absorbing element should be thermally connected with the heating elements of the heat radiator or generator, and that back 4, which performs that function in the embodiment shown in the drawing is merely shown by way of example and could be replaced by any other equivalent means.

Generally speaking, it should be well understood that while I have disclosed what I deem to be a practical and efficient embodiment of my invention, it should be well understood that I do not wish to be limited thereto as there might be changes made in the arrangement, disposition and form of the parts without departing from the principle of my invention as comprehended within the scope of the appended claim.

What I claim is:

A device for humidifying the atmosphere of a room heated by means of a radiator, which comprises in combination, a reservoir adapted to contain a liquid to be evaporated for humidifying the atmosphere, said reservoir consisting of a box of very flat shape, one of the large faces of said box being prolonged upwardly so as to form a substantially plane support, the vertical edges of which are bent so as to form grooves, a panel of asbestos engaged in said grooves so as to be firmly applied against the inner side of said support, said panel extending downwardly to a certain distance into said box so as to dip in the liquid therein, and means for supporting the device in a vertical position.

MICHEL COHENDY.
